4 Claims. (Cl. 230—256)

My invention relates to fans driven by electric motors, and more particularly to fans which while being rotated also have an oscillating movement.

The object of the present invention is to provide means enabling one to readily control said oscillating movement so as to vary the oscillations of the fan from zero to the largest range of oscillation, without any interruption in the operation of the fan. This object I accomplish by simple and inexpensive means, as will appear from the following description of the invention.

On the annexed drawing, on which I have shown, by way of illustration an embodiment of my invention,

Fig. 1 is a side-view of the entire fan and its motor, Fig. 2 a section along line 2—2 in Fig. 1 on a greatly enlarged scale, Fig. 3 a section along line 3—3 in Fig. 2 and Fig. 4 a section along line 4—4 in Fig. 2.

As shown in Fig. 1, the oscillating fan, together with its driving motor indicated at 1, is mounted, by means of a holder 19 on a base B in such a way, that the fan can be tilted forwards and backwards. At 22 is shown a fastening screw for holding the fan in any position to which it may be tilted.

At 6 in Fig. 2 is shown a center pin, by means of which the casing of the driving motor 1 carrying the fan is journaled in the fixed holder 19 so that it can be oscillated. The said pin 6 has a square head shown at 7, which enters a rectangular slot 9 in a quadrant-shaped member 8, which can execute a sliding motion relative to the said pin 6.

At 2 is shown a revolving disk which by means of a reduction gear is continually rotated by the driving motor 1. At 3 in Fig. 2 is shown a link with one end eccentrically attached by a pivot to said revolving disk 2 and with its other end connected by a pivot 5 with a hollowed arm shown in Fig. 2 at 4. The other end of said arm 4 is connected by a pivot 10 with said quadrant-shaped member 8.

At 13 is shown a circular disk resting on the holder 19 and provided with a finger piece 16, whereby the said disk may be turned about the center pin 6 in either direction. The said disk has, as will be seen from Fig. 2, a circular slot 11 and a cam-shaped slot 12. At 14 in Fig. 3 is shown a stud, which passes through the cam-shaped slot 12 in disk 13 and engages in a segmental channel 15 provided on the underside of the quadrant-shaped member 8, while the head

14' of said stud engages in a straight radial groove 20 in the holder 19 so as to slide in said groove.

At 18 in Fig. 3 is shown a stud secured to the holder 19 and entering a straight groove 17 formed by the hollow arm 4, which, therefore, 5 can execute a sliding motion relative to said stud 18. The latter passes through the circular slot 11 in disk 13.

From the foregoing it will be understood that as the disk 13 by means of its finger-piece 16 is turned in a counter-clockwise direction as indicated by the arrow in Fig. 2, the cam-slot 12 in said disk, by reason of the stud 14 passing through said slot and engaging in the segmental channel 15 on the underside of the quadrant-shaped member 8 will impart to said member a sliding movement relative to the square head 7 of the center pin 6, whereby the hollowed arm 4 pivoted to member 8 will be moved from its full-line position shown in Fig. 2 to its broken line 20 position. In this position, the pivot pin 10 pivotally connecting the hollowed arm 4 with the quadrant-shaped member 8 will be in line with the stud 18, and as the disk 2 revolves, it will impart merely a rocking motion to the hollowed arm 4 about the pivot pin 10 without causing any oscillating movement of the motor casing and the fan by means of the quadrant-shaped member 8.

When now the slotted disk 13 by means of its finger-piece 16 is rotated in the clockwise direction in Fig. 2, the quadrant-shaped member 8, by means of the stud 14 through its cooperation with the cam-slot 12 and the segmental channel 15 on the underside of member 8, will be caused to slide in the other direction, and the hollowed arm 4 will be moved back to its full-line position shown in Fig. 2, in which the pivot pin 5 connecting the link 3 with arm 4 will be in line with the stud 18 as shown in Fig. 3. In this position there will be no rocking motion of the arm 4 so that as the disk 2 revolves, the motor casing 1 together with the fan will be oscillated back and forth by means of the link 3 and arm 4 through its greatest angle. It will be readily seen that this angle can be nicely varied by the slotted disk 13 being turned to intermediate positions as indicated by the graduation lines shown in Fig. 2, so that the fan while operating may be oscillated from zero to its greatest angle.

While I have shown and described a preferred embodiment of my invention, the same is, of course, capable of modifications which fall within the scope of the appended claims, in which the invention is defined in its essential features.

I claim:

1. In an oscillating fan, the combination with the motor, a fan driven thereby, and a holder pivotally supporting the motor and the fan, of a revolving disk apart from said motor being rotated thereby, a sliding member adapted to be shifted relative to the pivotal axis of the fan, a link operatively connecting said sliding member with said revolving disk, a rotatable disk having a cam-slot operatively associated with said sliding member, and means for turning said rotatable disk in either direction so as to cause the shifting of said sliding member to thereby vary the range of oscillations.
2. In an oscillating fan, the combination with the motor, a fan driven thereby, and a holder pivotally supporting the motor and the fan, of a revolving disk apart from said motor being rotated thereby, a sliding member adapted to be shifted relative to the pivotal axis of the fan, an arm pivoted to said sliding member, a link jointed to said arm and operatively connecting thereby said sliding member with said revolving disk, a rotatable disk having a cam-slot operatively associated with said sliding member, and means for turning said rotatable disk in either direction so as to cause the shifting of said sliding member to thereby vary the range of oscillations.
3. In an oscillating fan, the combination with the motor, a fan driven thereby and a holder pivotally supporting the motor and the fan, of a revolving disk apart from said motor being rotated thereby, a sliding member adapted to be

shifted relative to the pivotal axis of the fan, a link operatively connecting said sliding member with said revolving disk, a stud engaging both a segmental channel on said sliding member and a straight radial groove in said holder, a rotatable disk having a cam-slot engaging said stud, and means for turning said rotatable disk in either direction so as to cause the cam-slot in said disk to shift said sliding member being guided by said stud moving in the radial groove to thereby vary 10 the range of the oscillations.

4. In an oscillating fan, the combination with the motor, a fan driven thereby and a holder pivotally supporting the motor and the fan, of a revolving disk apart from said motor being rotated thereby, a sliding member adapted to be shifted relative to the pivotal axis of the fan, an arm pivoted to said sliding member, a link jointed to said arm and operatively connecting thereby said sliding member with said revolving disk, a 20 stud engaging both a segmental channel on said sliding member and a straight radial groove in said holder, a rotatable disk having a cam-slot engaging said stud, means for turning said rotatable disk in either direction so as to cause the 25 cam-slot in said disk to shift said sliding member being guided by said stud moving in the radial groove to thereby vary the range of the oscillations, and a second stud fixed in said holder and engaging a groove in the underside of said arm, 30 said second stud entering a segmental slot in said rotatable disk.

YOSHITERU SHU.
